(57) **CLAIM**

We claim the ornamental design for a head-mounted display with adjustable and swappable battery temples, as shown and described.

DESCRIPTION

FIG. 1 is a first perspective view of the head-mounted display with adjustable and swappable battery temples embodying the new design.

FIG. 2 is a second perspective view of the head-mounted display with adjustable and swappable battery temples embodying the new design.

FIG. 3 is a frontal view of the head-mounted display with adjustable and swappable battery temples embodying the new design.

FIG. 4 is a rear view of the head-mounted display with adjustable and swappable battery temples embodying the new design.

FIG. 5 is a first side view of the head-mounted display with adjustable and swappable battery temples embodying the new design.

FIG. 6 is a second side view of the head-mounted display with adjustable and swappable battery temples embodying the new design.

FIG. 7 is a top view of the head-mounted display with adjustable and swappable battery temples embodying the new design.

FIG. 8 is a bottom view of the head-mounted display with adjustable and swappable battery temples embodying the new design.

FIG. 9 is an exploded perspective view of the head-mounted display with adjustable and swappable battery temples embodying the new design; and,

FIG. 10 is an exploded side view of the head-mounted display with adjustable and swappable battery temples embodying the new design.

The broken lines are for the purpose of illustrating portions of the article that form no part of the claimed design.

1 Claim, 8 Drawing Sheets
